(57) **CLAIM**

The ornamental design for a support for a purse as shown and described.

DESCRIPTION

FIG. 1 is a top plan view of an embodiment of a support for a purse showing my new design in an unfolded position. FIG. 2 is a top plan view of the embodiment of FIG. 1 in a folded position.

FIG. 3 is a bottom plan view of the embodiment of FIG. 1 in the unfolded position.

FIG. 4 is an end view of the embodiment of FIG. 1 in the unfolded position, the opposing end view being a mirror image.

FIG. 5 is a side view of the embodiment of FIG. 1 in the unfolded position, the opposing side view being identical. FIG. 6 is a bottom plan view of the embodiment of FIG. 1 in the folded position.

FIG. 7 is an end view of the embodiment of FIG. 1 in the folded position, the opposing end view being a mirror image.

FIG. 8 is a side view of the embodiment of FIG. 1 in the folded position, the opposing side view being identical.

FIG. 9 is a top plan view of a second embodiment of the support for a purse in an unfolded position.

FIG. 10 is a top plan view of the second embodiment in a folded position.

FIG. 11 is a bottom plan view of the second embodiment in the unfolded position.

FIG. 12 is an end view of the second embodiment in the unfolded position, the opposing end view being a mirror image.

FIG. 13 is a side view of the second embodiment in the unfolded position, the opposing side view being identical.

FIG. 14 is a bottom plan view of the second embodiment in the folded position.

FIG. 15 is an end view of the second embodiment in the folded position, the opposing end view being a mirror image; and,

(Continued)

FIG. 16 is a side view of the second embodiment in the folded position, the opposing side view being identical. The elements shown in broken lines depict portions of the support for a purse that form no part of the claimed design.
